UNITED STATES PATENT OFFICE.

KARL SCHAREENBERG, OF KONIGSBERG, GERMANY.

RAILWAY-CAR COUPLING.

Application filed February 24, 1925. Serial No. 11,236.

This invention relates to railway car buffer couplings and more particularly to the type in which each coupler is a counterpart of the other and has a link pivoted on a swinging hookplate, the link of one coupler being adapted to engage the hookplate of the other coupler. One object of my invention is to provide means for preventing the couplers attaching themselves together when it is desired merely to shunt the cars without coupling them together.

In the drawings, Figure 1 is a sectional plan view of two couplers in normal operative position about to come in contact with each other;

Figure 2 is another plan view showing the couplers in the ready-for-coupling position;

Figure 3 shows the couplers fastened together, while,

Figure 4 shows the first phase of the uncoupling,

Figure 5 the shunting position and

Figure 6 shows the position of the coupling members for separating from the shunting position.

Heretofore railway car couplings of this type would automatically couple up when pressed together, even if one coupler were in operative position and one were closed.

This is a disadvantage if it is desired to shunt the cars about without coupling them together, and it is one object of this invention to so modify the construction that the couplers can, if desired, be set in a position where they will come together without coupling up and can then be coupled up only by first separating them.

Each coupler has a casing *g* adapted to act as a buffer and containing the coupling elements. There is a hookplate pivoted on the casing with a tension spring *e* tending to hold it in the normal operative position shown in Figure 1. The two hookplates are designated by the reference letters *a* and *a'* respectively. In one edge of each hookplate is a notch having a back lip *b*. Each spring *e* is fastened to the hookplate on the side where the notch is located. Pivoted to the opposite side of each hookplate is a link, the link on the hookplate *a* being designated by the reference letter *d*, and the link on hookplate *a'* by the letter *d'*. The casing over the notch in each hookplate is in the form of a funnel *f* and *f'* leading to the notch in the hookplate. The novel detail of

construction lies in the size of the back lip *b* of the notch in each hookplate. Heretofore this back lip has been so large that when the notch has been turned forward, the link 60 could not pass between the lip and the casing. In my improved construction this back lip is cut sufficiently small to permit the link to pass between the casing and lip if the notch is turned forward by hand a little beyond the position to which it is forced by the coming together of the two couplers. It will be apparent that the end of link *d* cannot engage the notch, in the hookplate *a'* as long as the link *d'* lies between the hook- 70 plate *a* and the casing *g*, because only the forward convexity of the hookplate *a'* is presented to the link *d*. By these means the couplers can be brought together to act as buffers while the cars are being shunted 75 about, without their coupling up. This has hitherto been impossible with this type of coupler.

To put the couplers into the normal operative position again, it is only necessary to 80 separate them, when they will return to the position shown in Figure 1 under the influence of the springs *e*.

When the couplers are in normal operative position and are brought together, the 85 ends of the links *d* and *d'* will come in contact with the forward convexities of the hook plates *a'* and *a*, and as the couplers are brought together, the links will therefore cause the hook plates to be turned against 90 the tension of the springs *e'* and *e* until the couplers assume the position shown in Fig. 2. The ends of the links *d* and *d'* will then drop into the notches in the hookplates *a'* and *a*, respectively, and the springs *e'* and *e* 95 will pull the hook plates back to the position shown in Fig. 1 leaving the couplers fastened together as shown in Fig. 3.

If it is desired to unfasten the couplers in order to shunt the cars about without 100 their being coupled up, a handle *k* on the hook plate *a* or a handle *k'* on the hook plate *a'* is turned by hand: the handle *k* being used in the example shown in the drawings. When its is desired to uncouple 105 the couplings, the handle *k* is pushed back in the direction shown by the arrow in Fig. 4 until the hook plate *a* is turned to such an extent that its rear or back lip *b* has not only turned the hook plate *a'* until that plate 110 has released the link *d* but until the end of the link *d* has been forced out of the notch

and over the back lip *b* of the hook plate *a*. At this moment the parts are in the position shown in Fig. 4 but instantly the spring *e*¹ turns the hook plate *a*¹ pushing the link *d*¹ between the casing *g* and the hook plate *a* (see Fig. 5). The coupling elements will remain in these positions until the couplers are separated, the instant of separation when the couplers have been in the position shown in Fig. 5 being shown in Fig. 6. When the couplers are thus separated, the spring *e* will turn the hook plate *a* back into its original operative position as soon as the link *d*¹ passes the back lip *b*. Once this has been accomplished the couplers are in position to automatically fasten together as soon as the couplers are again brought together.

I claim:

1. A car coupler having a casing, a hook-
20 plate pivoted in said casing, in combination
with a link pivoted on said hookplate and
adapted to engage the hookplate of a counter
coupler, and a spring tending to keep said
hookplate in operative position, the hook on
25 the hookplate being shaped to permit the

link of the counter coupler to pass between it and the casing when the hookplate is turned forward beyond the ready-for-coupling position and the coupler brought into bearing contact with the counter coupler.

2. A car coupler having a casing adapted to act as a buffer, a hookplate pivoted in said casing having a notch therein in combination with a link pivoted on said hookplate and adapted to engage the notch in the hookplate of a counter coupler, and a spring tending to keep said hookplate in operative position; the back lip of the notch in the hookplate being cut small enough to permit the link of the counter coupler to pass between it and the casing and prevent engagement between the link of the coupler and the notch of the hookplate of the counter coupler, when said hookplate is turned forward beyond the ready-for-coupling position, substantially as described.

In testimony whereof I have signed my name to this specification.

KARL SCHARFENBERG.
